UNITED STATES PATENT OFFICE

DAVID S. ANTHONY, OF SAN ANTONIO, TEXAS

AUTOMATIC SHARPENER

Application filed July 6, 1926. Serial No. 120,751.

This invention relates to improvements in devices for sharpening grinding plates or burrs of grist mills, and particularly that type of plate which is formed of chilled cast iron and having its surface provided with machined cutting grooves or corrugations. As far as I am aware no machine has been provided for sharpening these plates.

It is the object of my invention to provide a small and compact machine, which I shall term an automatic sharpener, of simple and rigid construction, which may be owned and operated by the miller, thereby avoiding the expense and delay of sending the plates to a shop to be sharpened.

A further object is to provide a sharpener which will operate automatically after the plate has been placed in position until it has become completely sharpened.

20 A further object is to provide in a planer adapted to sharpen grinding plates, means for automatically alining the cutting teeth of the plate with the cutting tool.

25 A further object is to provide in a planer improved means for actuating the movable table.

A further object is to provide in a sharpener improved means for regulating the depth of the cut of the tool.

30 My invention consists in the construction, arrangement and combination of the various parts of the device, whereby the objects contemplated are attained, as hereinafter more fully set forth, pointed out in my claims, and illustrated in the accompanying drawings, in which:

Figure 1 is a plan view of my improved planer.

40 Figure 2 is a side elevation of the same.

Figure 3 is a detail sectional view taken on the line 3—3 of Figure 1.

Figure 4 is a detail sectional view taken on the line 4—4 of Figure 3.

45 Figure 5 is a detail sectional view taken on the line 5—5 of Figure 2.

Figure 6 is a detail sectional view taken on the line 6—6 of Figure 2.

50 Figure 7 is an enlarged, detail, side elevation of the cutter head and the mechanism

for throwing the same into inoperative position.

Figure 8 is an end elevation of the cutter head, a portion of which is broken away to show the manner in which the cutting tool is secured therein.

My improved sharpener comprises a base 10 formed hollow and having side members 11 and end members 12 and 13. The base is mounted on suitable skids 14, one end of the skids being provided with a platform 15 designed to carry an electric motor 16 from which power for operating the planer is derived.

The forward end of the top edge of the members 11 is provided with horizontal guides 17, while the back end of the upper edge of said members 11 is provided with an upwardly extending portion 18 designed to provide hinge members and what I shall term the head support 19. Said head support 19 is provided with side members 20, the back ends of which are pivotally mounted to the members 18 by means of a shaft 21. The top portion of the member 19 is provided with an opening 22 which is beveled at its upper end and is designed to receive a vertical shaft 23, the lower end of which is provided with an eye 24 designed to receive a shaft 25. The shaft 25 is mounted in the side members 11. The upper end of the shaft 23 is screw threaded and designed to carry an adjusting nut 26, the upper end of which has outwardly extending hand members 27. The shaft 23 is also provided with a collar 28 for the purpose of supporting the lower end of a spring 29 mounted on the shaft 23, said spring having its upper end resting against the under surface of the head 19.

The front face of the member 19 is provided with forwardly extending ears 30, between which the cutter head 31 is pivotally mounted by means of a shaft 32. Said head is provided with a vertical slot 33 which terminates at its lower end in a dove tail groove 34 for supporting the cutting tool 35. The head 31 is designed to rest normally in a vertical position with the tool 35 inclined slightly relative to the horizontal. The side edges of the tool 35 are beveled to fit the groove

34. A set screw 36 is mounted in the lower end of the member 31 and provides means for rigidly clamping the cutter 35 in position.

By this arrangement it will be seen that 5 the lower end of the cutter head 31, together with the cutter 35, is free to swing forwardly and upwardly from the vertical position shown in Figure 3. The rearward movement of the cutter head is limited by means 10 of the set screw 37 mounted in the lower end of the head 19, the outer end of said set screw being designed to engage the rear end of the cutter 35, and to provide means whereby any variation in the length of the cutter may be 15 compensated for, due to the shortening of the same by sharpening, so that the cutter 35 may always be made to assume the proper cutting angle.

Slidably mounted on the guides 17 is a 20 table 38, which is mounted beneath the cutter 35 a slight distance and designed to operate forwardly and rearwardly. The back edge of the under surface of the table 38 is provided with a downwardly projecting pin 25 39 having a roller 40 rotatively mounted thereon. Mounted transversely in the central portion of the base 10 is a trough 41 for the purpose of receiving the oil. The bottom of the trough 41 is provided with an 30 upwardly extending hub 42 in which an upwardly extending vertical shaft 43 is rotatively mounted. The upper end of said shaft is provided with a cam 44 supported in operative relation with the roller 40. Said cam 35 44 is provided with a downwardly extending hub 45 rotatively mounted in a bearing 46. The shaft 43 is also provided with a worm gear 47 mounted between the upper end of the bearing 42 and the lower end of the hub 40 45. Said worm gear 47 and the cam 44 are rigidly secured to said shaft by means of a key 48. The worm gear 47 is operated through a worm 49 mounted on a horizontal shaft 50, rotatively mounted in bearings 51 45 and 52 in the side members 11. The bearing 52 is provided with a packing gland 53 for preventing oil from the container 41 from escaping through the bearing. The outer end of the shaft 50 is provided with a belt wheel 50 54 which is in line with a pulley 55 of the motor 16, said belt wheels being operatively connected by a belt 56.

By this arrangement it will be seen that 55 as the cam 44 is rotated through the driving mechanism just described, the table 38 will be moved inwardly. The cam 44 is so shaped that the inward movement will be of uniform speed while the said cam is making about $\frac{7}{8}$ th of one complete revolution, after 60 which the table 38 is rapidly moved outwardly by means of spring 57 mounted on the outside of the base 10, the rear ends of the springs being secured to the said base by means of pins 58. The forward end of each 65 set of springs is provided with a chain 59 de-

signed to pass over a sheave 60 and has its free end secured to the under edge of the table 38 by means of a rivet 61. The chain 59 and the pulley 60 are provided so that comparatively long springs 57 may be employed, which may be arranged conveniently adjacent to the side members 11, in the manner clearly illustrated in Figures 1 and 2. Thus means is provided whereby the table 38 may be moved inwardly very slowly and 75 may be returned very rapidly, so that about $\frac{7}{8}$ th or more of the operating time is actually used in useful work.

Slidably mounted on top of the table 38 is what I shall term an auxiliary table 62, having one of its side edges provided with a pair of slotted lugs 63 and its other edge with a slotted lug 64. The slots of these lugs are provided with set screws 65, which are mounted in the table 38 and provide means whereby the said auxiliary table may be adjusted relative to the top of said table and transversely with the movement of the same, for the purpose hereinafter made clear.

The central portion of the auxiliary table 62 is provided with an upwardly extending lug 66. Pivotaly mounted on the lug 66 is a disk 68 having an upwardly projecting bolt 67, and its periphery provided with ratchet teeth 69 and its upper surface provided with an annular rib 70. The under surface of said disk 68 and the upper edge of the rib 70 are machined smooth. The upper and lower surfaces of the auxiliary table also is machined, as well as the top surface of the table 38.

The upper face of the rib 70 is designed to support a grinding plate 71. The under face of the plate 71 is also machined to fit the rib 70. This grinding plate is formed annular and has its inner edge slightly beveled at 72, said beveled portion being designed to receive the beveled edge of a washer 73, said washer being mounted on the bolt 67 and secured in position by means of a nut 74. This provides means whereby the grinding plate 71 may be rigidly secured to the disk 68, and at the same time centered exactly with the bolt 67. The upper surface of the grinding plate 71 is provided with a series of cutting grooves 75. These grooves are usually cut parallel with the back of the member 71 and tangentially with the center of said disk. These grooves are arranged in groups, the grooves of each group being parallel. The cutter 35 is provided with the same number of cutting teeth that there are grooves in each group on the grinder plate, so that each group of grooves may be sharpened by a single inward stroke of the cutter.

It will be seen from the drawings that the grinding plate will be moved toward and from the cutter 35 on account of the movement of the table 38 in a line parallel with the teeth of said cutter. The teeth, however,

of the grinding plate are arranged tangentially with the center of said plate. It is, therefore, necessary that the bolt 67 be moved in a line to one side of the longitudinal center line of the cutter. This is accomplished by 5 adjusting the auxiliary table transversely by means of the set screws 65, so that the teeth 75 will be in line with the teeth of the cutter 35, after which the set screws may be permanently set. It will further be seen from 10 the drawings that there is one tooth 69 for each group of teeth 75 so that each time the table 38 is moved inwardly the group of teeth opposite the cutter 35 will be engaged by 15 said cutter and sharpened. One of the teeth 69 will be caused to engage a pawl 76 rigidly secured to the base 10 by means of a bracket 77. The said pawl 76 is adjustably secured thereto by means of bolts 78, the pawl being 20 formed of yieldable metal so that it will yieldably engage the teeth 69. As the table 38 is moved outwardly, it will be seen that one of the teeth 69 will be engaged by said pawl and the disk 68 caused to rotate, which 25 in turn will cause the grinding plate 71 to be rotated and a new group of teeth 75 moved to position below the cutter 35.

It will be seen, however, that the rotation of the disk 68 takes place while it is being 30 moved outwardly and at the time while the teeth of the cutter 35 are in engagement with the teeth 75 of the grinding plate, and would cause the said teeth to be stripped from the plate if the cutter 35 were not elevated. To 35 cause said cutter 35 to disengage the teeth 75, I have provided a rock shaft 79 rotatively mounted in suitable bearings 80 of the head 19. The inner end of the rock shaft 79 is provided with a rock arm 81 having a slot 40 82 in its free end, said arm lying adjacent to one face of the member 31. A pin 83 is mounted in the member 31 and extends through the slot 82. The outer end of the shaft 79 is provided with a downwardly extending rock arm 84 having an outwardly projecting pin 85. The table 38 is provided 45 with a pair of trip bars 86 and 87, each of which is adjustably connected to said table by suitable set screws 88. The bar 86 is provided with an upwardly projecting arm 89 designed to engage the pin 35. The bar 87 is provided with an upwardly projecting arm 90 which will engage the pin 85 just at the time the table 38 is moved to its inner 50 limit of movement, causing the lower end of the arm 84 to be moved inwardly and the upper end of the arm 81 to be moved outwardly, which in turn will cause the lower end of the cutter head 31 to be elevated and 55 moved outwardly and upwardly, and caused to disengage the teeth 75. The arm 89 will be caused to engage the pin 85 at a time just before the outward movement of the table 38 takes place. This will cause the rock arms 60 81 and 84 to be moved in a reverse direction

and the member 31 to be lowered into operative position in line with a new group of teeth to be sharpened. The rotation of the grinding disk takes place while the cutter 35 is elevated, thereby eliminating any stripping of the teeth due to the rotary movement 70 of said disk.

Due to the fact that the movement of the grinding plate relative to the cutter is tangentially with the center of said cutter, it 75 will be seen that there is considerable tendency toward rotating the grinding plate about its pivot center in a counter-clockwise direction, as shown in Figure 1, as the cutting operation takes place. This rotating tendency is overcome by providing a spring actuated dog 91 pivotally secured to the auxiliary table 62.

It will further be seen that it is essential 80 that the tooth 69 be caused to engage said dog 91 firmly before the cutter 35 engages the teeth 75, to prevent any rotary movement of said disk, after the disk has moved into engagement with said cutter. The pawl 76 is so adjusted that the tooth adjacent to 85 the dog 91 will be moved a slight distance past the said dog to permit proper setting of the dog. Means is provided for slightly rotating the disk rearwardly to cause the tooth to engage said dog, which comprises 90 a lever 92 pivoted to an outwardly extending arm 93 which is also secured to the auxiliary table 62. The inner end of the arm 92 is provided with a roller 94 designed to 95 engage one of the teeth 69. A spring 95 is 100 provided for applying yieldable pressure to said roller. The parts are so adjusted that when the dog 91 drops into position the roller 94 rests on the outer edge of one of the teeth 69, so that rotary motion is imparted to 105 said disk, causing the tooth 69 to engage the dog 91, thereby providing means whereby the disk, together with the grinding plate, will be firmly supported in operative relation before the cutter engages the teeth of the grinding plate. 110

On account of the head 19 being pivotally connected to the base 10, it will be seen that means is provided whereby the depth of the cut of the cutter 35 may be adjusted by 115 means of the head 26 and the screw threaded shaft 23. The spring 29 serves to support the head in an elevated position. All of these parts are rigidly constructed as the cutting strain is very severe. 120

It is sometimes desirable to make one or more trial cuts when the grinding plate is first placed into position without rotating the disk 62. To accomplish this I have provided 125 a hand lever 96, the lower end of which is pivotally connected to the pawl 76. Said hand lever is provided with an inwardly projecting lug 97 designed to engage a cam shaped sector 98 so that as the top of the handle is swung either forwardly or rear- 130

wardly, the outer end of the pawl 76 may be brought into or out of engagement with the teeth 69 of the disk 68, thereby providing means whereby the said pawl may be thrown 5 out of engagement with said teeth and permit the table 38 to be operated without rotating said grinding plate.

Thus it will be seen that I have provided a planer of simple, durable and inexpensive 10 construction, which may be operated by an inexperienced operator, the only requirement being to place the grinding plate in position on the disk 68 which may be easily and quickly done with the centering plate 73 15 and the nut 74. In order to properly time the grinding member 71 with the disk 68 an upwardly projecting pin 98 is provided which extends into a recess 99 in the under surface of the plate 71, after which the motor 20 may be started and the machine will work automatically to sharpen the plates.

It will be seen that by providing the cam 44 for operating the table 38, I have provided means whereby a slow and powerful 25 uniform movement may be imparted to the table and to the grinding plate. The springs 57 provides means whereby the table may be rapidly returned.

I claim as my invention:

- 30 1. In a device of the class described, a base, a table mounted to slide horizontally on said base, a driving shaft rotatively mounted in said base, a vertical shaft beneath said table, gear mechanism for imparting rotary movement from said driving shaft to said vertical shaft, a cam supported on the upper end of said vertical shaft, a roller projecting downwardly from said table to engage said cam for imparting cutting movement to said table in one direction as said cam is rotated, yieldable means for moving said table through its return stroke, an auxiliary table adjustably mounted for transverse movement on the first table, said auxiliary table being provided with an upwardly projecting pivot, a stock supporting disk rotatively mounted on said pivot and supported on the upper surface of said auxiliary table, said disk having its periphery provided with 45 ratchet teeth, and its central portion provided with an upwardly projecting bolt, a washer slidably mounted on said bolt having its periphery beveled, means for imparting intermittent rotary movement to said disk in one direction, a retaining pawl in contact with said ratchet teeth, and spring actuated means for moving one of said ratchet teeth into firm engagement with said pawl.
- 50 2. In a device of the class described, a base, a head support having one end pivotally mounted to said base, a cutter head pivotally mounted to the free end of said head support, a screw threaded shaft having one end pivotally mounted in said base and its screw 55 threaded end slidably mounted in said head

support between its pivot end and its free end, yieldable means on said shaft for imparting outward movement to said head support, an adjusting nut on the outer end of said threaded shaft, said cutter being mounted horizontally in said head, a table slidably mounted on said base to move toward and from said cutter, means for imparting a substantially uniform and positive movement to said table to cause it to move toward said cutter, yieldable means for returning said table, means for rotatively clamping stock on said table, and means for automatically imparting predetermined rotary movement to said stock on the return stroke of said table.

3. In a device of the class described, a base, a head support having one end pivotally mounted to said base, a cutter head pivotally mounted in the free end of said head support, means for clamping a horizontal cutter in said cutter head, means for adjusting said cutter longitudinally, a screw threaded shaft having one end pivotally mounted in said base and its opposite end slidably mounted in said head support between its ends, a spring carried on said shaft for imparting outward movement to said head support, a nut on the threaded portion of said shaft for adjusting the free end of said head support, a table slidably mounted in said base, means for imparting positive movement to said table to cause it to move toward said cutter, yieldable means for imparting return movement to said table, means for supporting and rotating stock on said table, means for imparting predetermined rotary movement to said stock on the return stroke of said table, and means actuated through the movement of said table for moving said cutter out of operative relation with said stock while rotary movement is being imparted to the stock.

Des Moines, Iowa, June 2, 1926.

DAVID S. ANTHONY.

- 60 65 2. In a device of the class described, a base, a head support having one end pivotally mounted to said base, a cutter head pivotally mounted to the free end of said head support, a screw threaded shaft having one end pivotally mounted in said base and its screw threaded end slidably mounted in said head
